UNITED STATES PATENT OFFICE.

CHARLES E. FOOTE, OF NUNDA, NEW YORK, ASSIGNOR TO THE FOOTE COMPANY, INC., OF NUNDA, NEW YORK, A CORPORATION OF NEW YORK.

DISTRIBUTING BUCKET FOR CONCRETE PAVERS.

Application filed April 2, 1925. Serial No. 20,142.

To all whom it may concern:

Be it known that I, CHARLES E. FOOTE, a citizen of the United States, residing at Nunda, in the county of Livingston and State of New York, have invented certain new and useful Improvements in Distributing Buckets for Concrete Pavers, of which the following is a specification.

My invention relates to new and useful improvements in distributing buckets for concrete pavers and is a companion of an application filed by me on March 30, 1925, bearing Serial Number 19,342.

The present invention relates to a distributing bucket having pivotal bottom doors, a trolley for supporting the bucket in its to and fro movement on a boom, a cross shaft on the trolley, a tripping mechanism in the form of a segment mounted on this shaft, and means extending from the bucket doors to this shaft so that a rocking of the shaft by this segment will cause the doors to open and close as desired.

The invention is an improvement on the bucket shown in the patent granted to me on January 30, 1923, No. 1,442,354.

The operation of the segment in the present invention is similar to the mode of operation shown in the above mentioned patent, that is, there is a cable secured to the opposite ends of the segment and to a drum so that a stopping of the drum as the bucket moves along the boom will cause the segment to partly revolve and thereby open or close the doors; but instead of mounting the segment only on the cross shaft and providing an arm in the form of a yoke connected to the segment, and instead of providing a cross head and side members as shown in my previous patent, I extend the length of the shaft and mount the segment thereon, and also provide two short stub arms on the shaft to which in turn are secured side members that extend downwardly of the sides of the bucket and are secured to the doors. Spring means, however, are interposed in the side members so that the doors will be resiliently held in their closed position.

In a number of forms of buckets now in use, spring means are interposed between the tripping mechanism and a yoke or side members which extend to the opposite ends of the door or doors, and if there is any sagging, the door or doors will sag as a

whole throughout their length. With my construction about to be described, should any concrete stick between the bucket and the doors, one end may sag slightly without affecting the other end and the offending material may be quickly removed and the door made to assume its proper position.

In the present invention also, I do away with a cross head or an extra shaft as shown in a number of forms of buckets, and mount the side members of the doors directly upon the shaft which supports the segment, thus providing a more economical construction, and also making it easy to trip the shaft by a hand lever when desired, which was practically impossible with my old style bucket.

One of the objects, therefore, of the present invention, is to provide a bucket supported by a trolley adapted to move to and fro on a boom, the trolley having a single central cross shaft on which is mounted a segment and from which shaft extends the side members down along the sides of the bucket to the doors, the side members having incorporated therein springs to add a resilient action to the closing and supporting of the doors.

Still another object of the invention is to provide a bucket which may be readily tripped by a hand lever, readily tripped by a cable as shown in my previous patent, and also tripped automatically by means at the inner end of the boom so that the doors of the bucket will always be closed when the bucket is in position to receive the aggregates.

With these and other objects in view, the invention consists in certain new and novel constructions and combination of parts as will be hereinafter more fully described and pointed out in the claims.

Referring now to the drawings showing a preferred embodiment of my invention,

Fig. 1 is a side elevation showing a fragmentary portion of a paver having a boom extending therefrom and on which is shown my improved bucket, the doors being shown in their open position, the dotted lines showing the bucket approaching the inner end of the boom to be automatically tripped, so that the doors will be in their closed position when the bucket is at the inner end of the boom.

Fig. 2 is an end view of my improved

bucket, showing the manner of supporting and operating the doors, and

Fig. 3 is a side elevation of my improved bucket with the doors shown in their closed 5 position.

Referring now more in detail to Fig. 1, there is fragmentarily shown a portion of a paver comprising an upright 1, a portion of a frame 2, a small platform 10 3, and a lower platform 4, while mounted on this lower platform 4 and arranged for horizontal movement as well as vertical adjustment, is a boom 5, similar to the boom shown in my patent of January 30, 1923, No. 1, 15 443,354, and similar to the boom shown in the application filed by me on March 30, 1925, bearing Serial No. 19,342.

Located on this boom 5 is a trolley 6 to which is secured a bucket 7 by the straps 8. Secured to the opposite end of the trolley 6 20 are the ends of the cable 9 which cable extends under sheaves 10 and upwardly over sheaves 11 where the cable then passes over and under, and is secured to a drum 12 25 shown in dotted lines, which drum is mounted on the platform 3.

This drum and its mode of operation form the subject matter of the aforementioned application, Serial No. 19,342. The purpose 30 of this drum and cable is to drive the bucket to and fro on the boom 5, while a second drum 13 is secured on the boom, as shown in my previous patent, over which passes a cable 14, which cable in turn is secured to 35 and passes over a trip member in the form of a segment 15, which segment is mounted on a cross shaft 16, which in turn is mounted in the trolley 6. Supporting means extend from this shaft down to the doors of the 40 bucket, as will shortly be described, and it will be understood that a tripping of this segment and a rocking of its shaft, will open and close the doors.

A brake band 17 is shown in Fig. 1 in 45 dotted lines, as being applied to this drum, the brake band in turn being fastened to a suitably mounted bell crank 18 so that an operation of this bell crank 18 by the rope 19 will apply the brake to the drum 13, and as the bucket moves along the boom, it being driven by the drum 12, and the drum 13 being stopped in its rotation as the bucket continues to travel, the segment 50 will be partly revolved and the doors opened, all of which will be clearly understood by referring to my patent above mentioned.

In my previous patent I showed the brake band connected to the drum being operated 55 by a foot pedal, whereas in the present application, I have shown the brake band applied by the operation of a rope extending over to the platform on which the operator stands.

In the present application also, I have

provided an automatic means for applying a braking pressure to this drum, which consists of extending a rod 20 through an eyelet 21 formed in the bell crank 18 and on the inner end of the rod are two bolts 22, while 70 the outer end of the rod is secured to a trip arm 23 that is pivoted as at 24 on the boom 5, this arm having a roller at its lower end adapted to contact with a plate 25 mounted on the trolley 6, so that when this trolley 75 6 approaches the inner end of the boom it will trip the arm 23 and through the rod 20 and the bell crank 18 apply the brake to the drum 13, causing the segment to return to its normal position, thus assuring that the 80 doors will be closed.

By providing the bell crank 18 with the eyelet 21, the rod 20 will simply work through the eyelet as the bucket moves outwardly so that no pressure will be applied 85 to the drum nor will the segment be tripped, as the bucket starts outwardly.

So far as the invention has been described, it follows closely the invention shown in my 90 previous patent, with the exception of the automatic tripping means.

Referring now more specifically to the manner of supporting and locking the doors of the bucket referred to and the tripping mechanism, and glancing at Fig. 2, there is shown the shaft 16 which is suitably mounted in the plates 26 of the trolley 6. This shaft is much greater in length than shown in my previous patent, and near 95 its outer end and beyond the sides of the plates, are the stub arms 27, while mounted between the plates on the shaft is the segment 15 heretofore referred to. Secured to these stub arms 27 are the side members or arms 28, these arms 28 being slightly offset 100 at their upper end as at 29 where they are secured to the stub arms 27. These arms or side members 28 are curved or deflected as at 29' and have their ends 30 bent outwardly as clearly shown in Fig. 2.

Extending respectively through the ends 105 30 are the bolts 31 of the couplers 32, and secured in the lower ends of each coupler are the upper ends of the rods 33, which rods extend downwardly and are pivotally connected at the lower ends to the ends of the doors 34, which doors are pivotally mounted as at 35 in the opposite sides of the bucket, and extend across the same.

Resting on the ends 30 of each side member 28, and about the bolts 31 of the couplers 32, are shown the springs 36 secured by the bolts 37 so that the weight of the doors are transmitted to the springs 36, thus providing a resilient action for the closing of the doors. Each end of the respective doors is therefore resiliently held, which is an advantage, as in case of any sagging or jam between the doors and the bottom of the 120 bucket, one end of a door may sag rather 125 130

than the door as a whole sag, which is the case in many of the different types of bucket now in use.

On one end of the shaft 16 there is shown 5 a handle 38 which makes it possible to rock this shaft 16 by hand to thereby open or close the doors and as the force from the handle is transmitted directly to this shaft 16, it is possible to open and close the doors 10 with comparative ease, which was not possible with my previous style of bucket, except with great exertion.

The operation of the bucket and its doors is comparatively simple, and it will be readily understood that when the segment 15 15 is in the position shown in Fig. 3, the side members, stub arms and cross shaft form a toggle arrangement, thus securely holding the doors in their closed position, while a 20 rocking of this segment rocks the shaft 16, and as the side members connected to the doors are directly connected by stub arms on this shaft, a rocking of the shaft will break the toggle and allow the doors to open 25 or vice versa.

Furthermore, by providing spring means within the side members, there will be a 30 resilient action in the opening and closing of the doors, and each end will be resiliently supported.

Again, it will be understood that the doors may be opened by rocking the shaft manually by the handle 38, that the segment may be operated by applying the 35 brake on the drum 13 to thereby trip the doors as the bucket moves, and lastly the segments and its shaft will be tripped by the plate 25 contacting with the arm 23 and applying the brake to the drum to close the 40 doors should they happen to be opened, as the trolley and bucket approach the inner end of the boom.

From the foregoing it will be seen that by mounting a cross shaft in a trolley and 45 extending the side members which are connected to the doors up to this cross shaft, I have done away with extra shafts and yokes and rods such as shown in my previous patent, thus cutting down the expense 50 of the construction, and furthermore I have made it possible to open these doors manually as the force will be transmitted directly to the shaft 16; also I have made it possible to resiliently support the respective ends of 55 each door which is an improvement over simply resiliently supporting the doors as a whole.

Many slight changes might be made without in any way departing from the spirit 60 and scope of the invention.

Having thus described my invention, what I claim as new and desire to secure by Letters Patent is:—

1. A distributing bucket for concrete 65 pavers comprising a trolley adapted to move

to and fro on a boom, a bucket supported by said trolley and having pivotal bottom doors, a cross shaft on said trolley and a segment rigidly secured on said cross shaft, means extending from the pivotal doors to 70 the outer ends of said cross shaft, said means, cross-shaft and segment forming a toggle arrangement for said doors, so that a movement of the segment will rock said shaft to thereby open and close the doors. 75

2. A distributing bucket for concrete pavers comprising a trolley adapted to move to and fro on a boom, a bucket supported by said trolley and having pivotal bottom doors, a cross shaft on said trolley, a segment secured on said cross shaft, stub arms 80 secured to said cross shaft near its outer ends and means extending from the pivotal doors to the said stub arms, said means, stub-arms, cross-shaft and segment forming 85 a toggle arrangement so that a movement of the segment will rock said shaft and thereby open and close the doors of the bucket.

3. A distributing bucket for concrete 90 pavers comprising a trolley adapted to move to and fro on a boom, a bucket supported by said trolley and having pivotal bottom doors, a cross shaft mounted in said trolley and extending outwardly beyond 95 the sides of the trolley, a segment rigidly secured on said cross shaft, stub arms secured to said cross shaft on its outer end, means extending from said stub arms downwardly on the opposite sides of the bucket 100 to said doors, so that a rocking of the cross shaft by said segment will respectively open and close the bucket doors, and a handle also on said cross shaft for manually rocking the same. 105

4. A distributing bucket for concrete pavers comprising a trolley to move to and fro on a boom, a bucket supported by said trolley and having pivotal bottom doors, a cross shaft on said trolley, a rocking means 110 on said shaft in the form of a segment, arms secured to said cross shaft near its outer ends, side members secured to said arm, rods connected to said side members and the doors, spring means interposed between said connections to provide a resilient action in the operation of said doors, and the operation of said segment rocking said cross shaft to thereby open and close the doors of the bucket. 115

5. A distributing bucket for concrete pavers comprising a trolley to move to and fro on a boom, a bucket supported by said trolley and having pivotal bottom doors, a cross shaft on said trolley, a rocking means 120 on said shaft in the form of a segment, stub arms connected to said cross shaft near its outer ends, forked-arranged rods respectively connected to the ends of the doors and on the opposite sides of the bucket, said 125

rods respectively connected to arms extending to the stub arms on the cross shaft, springs interposed in the connection between the arms and the fork-arranged rods 5 to thereby provide a resilient action to the several ends of the doors, and the rocking of the cross shaft opening and closing the doors of the bucket.

6. A distributing bucket for concrete pavers comprising a trolley moving to and fro on a boom, a bucket supported by said trolley, said bucket provided with laterally extending pivotal bottom doors, a cross shaft on said trolley, means on said shaft 10 for rocking the same, stub arms secured near the outer end of said shaft, supporting members being slightly bent at their upper ends secured to said stub arms, two links respectively situated on the opposite sides of the bucket and secured to said doors and to the lower ends of said supporting members, springs respectively interposed between said links and said supporting members to thereby resiliently support the opposite ends of the doors, and said shaft 15 holding the doors in their locked position until said shaft is rocked.

7. A bucket for concrete pavers comprising the bucket proper, pivotal doors at the bottom of said bucket, a trolley for supporting the bucket on a boom, a cross shaft in said trolley, members extending from said cross shaft downwardly to the opposite sides of said bucket, further members extending upwardly from the several ends of the pivotal doors, and spring couplers interposed between said downwardly extending members and said further members to provide a resilient supporting means for the several ends of the pivotal doors, and a rocking of the cross shaft opening and closing the doors of the bucket.

8. A distributing bucket for concrete pavers, comprising a trolley, a bucket supported on said trolley and having pivotal

doors, a cross shaft on said trolley, a toggle arrangement operably connected with said cross shaft and the pivotal doors of the bucket, the connection between the cross shaft and the doors of the bucket being in 50 the form of an inverted Y, and spring means interposed in the Y connection and near a point where a single leg of the Y merges into the double leg.

9. In combination with a boom and buck- 55 et, a trolley supporting said bucket, a cross shaft on said trolley, a segment on said cross shaft, a cable connected to said segment, said cable connected to a drum for operating said segment when said drum is 60 held against rotation, said bucket provided with pivotal bottom doors, means connecting the doors to said cross shaft so that a rocking of said segment opens and closes said doors, and an automatic trip mechanism located near the inner end of the boom 65 cooperating with said trolley to hold the drum against rotation to thereby rock the segment and close the doors as the bucket approaches its innermost position. 70

10. In combination with a boom and a bucket, a trolley for supporting said bucket, a cross shaft on said trolley, a tripping mechanism in the form of a segment 75 mounted on said shaft, the said bucket provided with pivotal doors, a toggle arrangement connecting said shaft with said doors for operating said doors when said shaft is rocked by said segment, a cable drum on said boom and connected with said segment for rocking said segment when desired, a lever pivotally mounted on said boom and operably connected with the said cable drum, said lever operated by the said trolley as it approaches the inner end of the boom to 80 thereby automatically operate the segment and close the doors of the bucket. 85

In testimony whereof I affix my signature.

CHARLES E. FOOTE.
